UNITED STATES PATENT OFFICE

152,506

DESIGN FOR A BLOUSE OR SIMILAR ARTICLE

Victor Tomshinsky, New York, N. Y.

Application July 13, 1948, Serial No. 147,520

Term of patent 3½ years

(Cl. D3—25)

To all whom it may concern:

Be it known that I, Victor Tomshinsky, a citizen of the United States of America, residing in New York, county of New York, and State of New York, have invented a new, original, and ornamental Design for a Blouse or Similar Article, of which the following is a specification, reference being had to the accompanying drawing, forming part thereof.

Fig. 1 is a front view of a blouse or similar article, showing my new design.

Fig. 2 is a rear view thereof.

Fig. 3 is a front fragmentary view of the blouse illustrating the collar portion in upward position.

I claim:

The ornamental design for a blouse or similar article, substantially as shown and described.

VICTOR TOMSHINSKY.
